(57) **CLAIM**

We claim the ornamental design for a waffle pop maker, as shown and described.

DESCRIPTION

FIG. 1 is a front view of a waffle pop maker of the present invention.

FIG. 2 is a right, side view of the waffle pop maker depicted in FIG. 1.

FIG. 3 is a left, side view of the waffle pop maker depicted in FIG. 1.

FIG. 4 is a rear view of the waffle pop maker depicted in FIG. 1.

FIG. 5 is a top view of the waffle pop maker depicted in FIG. 1.

FIG. 6 is a bottom view of the waffle pop maker depicted in FIG. 1.

FIG. 7 is a bottom, left perspective view of the waffle pop maker depicted in FIG. 1.

FIG. 8 is a top, right perspective view of the waffle pop maker depicted in FIG. 1.

FIG. 9 is a front view of the waffle pop maker depicted in FIG. 1 in an open disposition.

FIG. 10 is a top view of the waffle pop maker depicted in FIG. 1 in an open disposition; and,

FIG. 11 is a top, right perspective view of the waffle pop maker depicted in FIG. 1 in an open disposition.

The broken lines in the drawings illustrate portions of the waffle pop maker that form no part of the claimed design.
